FIG. 1 is a front perspective view of a seam ripper or similar article showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a cap-end view thereof, and

FIG. 7 is a handle-end view thereof.

The dominant features of my new design reside in the handle and cap portions shown in full lines in the drawing, while the conventional ripper blade is shown in broken lines.

I claim:

The ornamental design for a seam ripper or similar article, substantially as shown and described.
